UNITED STATES PATENT OFFICE.

HENRY H. MEYER, OF RED WING, MINNESOTA.

DEVICE FOR CARRYING MAIL.

1,086,928.

Specification of Letters Patent.

Patented Feb. 10, 1914.

Application filed June 14, 1913. Serial No. 773,797.

To all whom it may concern:

Be it known that I, HENRY H. MEYER, a citizen of the United States, residing at Red Wing, in the county of Goodhue and State 5 of Minnesota, have invented certain new and useful Improvements in Devices for Carrying Mail; and I do hereby declare the following to be a full, clear, and exact description of the invention, such as will enable others skilled in the art to which it 10 pertains to make and use the same.

This invention is in the nature of a device for carrying mail, and while it is especially intended for use on rural mail routes to 15 carry mail from the road along which the carrier travels to the houses of the patrons and back, it is equally well adapted for carrying mail or light merchandise between any two points within a reasonable distance 20 of each other.

The primary object of the invention is to provide improved means whereby mail brought by a carrier may be transported by hand power from the station on the road to 25 the residence of the patron in order to dispense with the necessity of the patron walking to the station, or the carrier walking to the residence, and thereby effecting a very great economy in time and labor.

30 The specific object of the invention will be particularly set forth hereinafter, and the invention consists in the improved construction, arrangement and combination of the parts of a device of the character specified, 35 which will be hereinafter fully described, and afterward specifically claimed.

In order that the construction and operation thereof may be readily comprehended, I will now proceed to fully describe my in- 40 vention in connection with the accompanying drawings, which illustrate an approved embodiment thereof, and in which drawings,

Figure 1 represents in elevation, the complete apparatus for conveying mail in accordance with my invention, the middle portion of the track wire, operating wire and posts being broken out to shorten the figure. Fig. 2 represents the same devices in plan view. Fig. 3 represents an enlarged sec- 45 tional view taken on a transverse plane cutting through the wires at any point thereon, said plane being indicated in Fig. 1 by the broken line 3-3. Fig. 4 represents an enlarged end elevation, the pole being broken 50 away. Fig. 5 represents a modified bracket.

Like reference characters mark the same parts in all of the figures of the drawings.

Referring specifically to the drawings, 5 indicates a pole of any ordinary form and construction, erected at the station or stop- 60 ping place of the carrier on a rural mail route, or at one terminal of the line, if used for other purposes, while 6 represents a pole erected at the residence of the patron of the rural mail route, or at the other terminal of 65 the line when used for other purposes, and 7 represents intermediate poles.

To the pole 5 is secured a substantially triangular bracket or supporting plate 8, while a similar bracket 9 is secured to the other 70 terminal pole 6. Attached to the brackets 8 are bearings 10 for an upright shaft 11, which carries at its upper end, a horizontal pulley or sheave 12, while at its lower end it carries a beveled pinion 13 which meshes 75 with a beveled gear 14 mounted on a shaft 15, journaled in the lower end of the bracket 8 and provided with a crank handle 16, or other suitable means by which it may be turned by hand. At the other terminal, 80 bearings 17 are provided for a vertical shaft 18 which carries at its upper end a horizontal pulley or sheave 19, of the same size as the pulley 12. The upright shaft with its gearing and crank handle may also be du- 85 plicated on the pole 6 if so desired, whereby the device may be operated from either end of the line.

Upon each intermediate pole 7 are secured on opposite sides horizontal brackets 20 90 which have at their outer ends vertical upwardly extending flanges 21. On opposite sides of the posts 7, at their upper ends, are secured outwardly inclined brackets 22 which at their outer ends are bent into vertical positions at 23, which lie against the flanges 21, and are secured thereto, the brackets 22 being continued from the bottom of said vertical portions 23 and turned upward at 24, forming horizontally extending 95 vertical arms 25 parallel with the vertical portions 23 before mentioned. Between the portion 23 and the vertical flange 25, at the lower end of the inclined brackets 22 on each side of the pole, is journaled a sheave 100 or pulley 26 and upon the upper edges of the vertical flanges 25, at the ends thereof, as clearly indicated in Fig. 1, is secured a wire or rod 27 which forms a track and which are secured at each end respectively in the 110

bracket 8, at their upper outer corners 28, the extended vertical flanges 25 forming bearings for the track wire on each side of each pole, whereby the number of poles necessary is decreased. It will be understood that there is a track wire 27 on each side of the line of posts and upon each of these track wires is mounted a trolley 29, carrying in its upper end a grooved pulley or sheave 30, journaled between the extended body of the trolley and its downwardly turned ends 31, and resting upon the track wire.

Mounted in the upwardly turned lower end 32 of a pair of trolleys 29, and removably secured therein in any suitable manner, is a mail box 33 which is cylindrical in cross section and provided with conical ends 34. The mail boxes may be made removable from the trolley frame in any suitable manner and may be provided with any approved form of door for giving access to the interior thereof.

Mounted around the sheaves 12 and 19 is an endless wire, cable, or rope, 35, wire being preferred, which in its normal position is extended from end to end of the line, such position being in line with eyes 35^a secured to the trolley, through which eyes said wires are passed, but inasmuch as the weight of the wire will cause it to sag, it will naturally drop in opposite directions from said eyes, and will be guided by the bracket 22 into position resting upon the top of the pulley or sheave 26, as indicated at 35^b in Fig. 3.

By turning the crank handle 16, the shaft 15, beveled gear 14, beveled pinion 13, shaft 11 and pulley or sheave 12, will be rotated, the diameter of the gear and pinion being regulated to give any desired speed to such rotation, and the stretches of wire 35 will be carried around with the pulley 12 and will carry the pulley 13 around with them, the opposite lengths of wire 35 thus traveling continuously in opposite directions so long as the crank handle is operated. Inasmuch as the wires 35 pass through the eyes 35^a, the trolley 29 and mail boxes 33 will be carried along with said propelling wires 35, so that, with one mail carrier on one wire, normally located at the station on the rural route and the other mail carrier at the residence of the patron, mail matter may be inserted in both boxes, when, by operating the propelling mechanism hereinbefore described, by turning the crank handle 16, one mail box will be propelled from the station on the rural route to the residence, and the other will be propelled in the opposite direction from the residence to the station. Any suitable signaling mechanism may be employed to notify the parties at the opposite end of the line when mail matter is to be delivered. It will be understood that the mail box which at one operation travels from the residence to the station, will then

take up its normal position at the station ready for the next operation, and that during the next operation the propelling mechanism will be turned in the opposite direction, and the direction of motion of the propelling wire will be opposite to that during the preceding operation so that there will be no necessity for returning the mail boxes from one station to the other after each operation as would be required with a single mail box and a single wire.

The bracket 22^a of Fig. 5 which may be substituted for bracket 22, consists of U-shaped sheet metal straddling the wire 27 and secured by crimping or squeezing the ends 22^b on the wire.

All of the parts of the invention are of the simplest character and there is no liability of breakage or disarrangement with ordinary use. Much time and labor is saved by the use of this invention, and while I have specifically described the exact construction and arrangement of the various component parts, it will be obvious to those skilled in the art to which the invention most nearly appertains, that changes and variations may be made therein within reasonable limits, without departing from the spirit and scope of the invention.

Having thus fully described my invention, what I claim and desire to secure by Letters Patent of the United States is:—

1. The combination with a series of poles, brackets secured upon the terminal poles, a track wire stretched on each side of the line of poles and secured in the outer upper corners of the terminal bracket, transverse downwardly extending outwardly inclined brackets on opposite sides of the intermediate poles of the line, said brackets being provided at their outer lower ends with vertical portions and thence turned upward forming vertical flanges extending horizontally in line of the wires on opposite sides of the poles, said horizontal brackets being provided with seats for the track wires at their opposite ends, trolleys mounted to travel on the track wires, mail boxes secured to the trolleys, eyes secured to the inner sides of the trolleys, horizontal grooved pulleys mounted on the terminal pole of the line and endless propelling wires mounted around said pulleys and passing through the eyes on the trolleys, and means for rotating the horizontal pulleys to drive the endless propelling wire.

2. The combination with a series of poles, brackets secured upon the terminal poles, a track wire stretched on each side of the line of poles and secured in the outer upper corners of the terminal bracket, transverse downwardly extending outwardly inclined brackets on opposite sides of the intermediate poles of the line, said brackets being provided at their outer lower ends with ver-

tical portions and thence turned upward forming vertical flanges extending horizontally in line of the wires on opposite sides of the poles, said horizontal brackets being 5 provided with seats for the track wires at their opposite ends, trolleys mounted to travel on the track wires, mail boxes secured to the trolleys, eyes secured to the inner sides of the trolleys, horizontal grooved pulleys 10 mounted on the terminal pole of the line and endless propelling wires mounted around said pulleys and passing through the eyes on the trolleys, means for rotating the horizontal pulleys to drive the endless pro-

15 pelling wire, and grooved supporting pulleys mounted in the brackets below the eyes on the trolleys, the inclined bracket serving as guides to direct the propelling wires on opposite sides of the eyes downward into contact with said pulleys in opposite directions from the eyes when said wires sag. 20

In testimony whereof I have signed my name to this specification in the presence of two subscribing witnesses.

HENRY H. MEYER.
